United States Patent Office

Des. 192,665
Patented Apr. 24, 1962

192,665

AIRCRAFT

Wieslaw Zenon Stepniewski, Springfield, Pa., assignor to
Boeing Airplane Company, Seattle, Wash., a corpora-
tion of Delaware

Filed Oct. 18, 1960, Ser. No. 62,522

Term of patent 14 years

(Cl. D71—1)

FIG. 1.

FIG. 2.

FIG. 3.

FIG. 1 is a front elevational view of an aircraft showing my new design;

FIG. 2 is a top plan view thereof;

FIG. 3 is a side elevation thereof; and

FIG. 4 is a top perspective view thereof illustrating the rear and side opposite that shown in FIG. 3.

I claim:

The ornamental design for an aircraft, substantially as shown.
